UNITED STATES PATENT OFFICE

2,021,138

MACHINE FOR OPERATING UPON SHEET METAL

Milton H. Ballard and Donald G. McLean, Beverly, Mass., assignors to United Shoe Machinery Corporation, Paterson, N. J., a corporation of New Jersey

Application June 29, 1931, Serial No. 547,546

3 Claims. (Cl. 164—23)

This invention relates to machines for operating upon sheet material and is herein illustrated as embodied in a press of the type commonly known as a clicking machine, such as that disclosed in United States Letters Patent No. 921,503, granted May 11, 1909, upon an application filed in the name of Arthur Bates, and illustrating a machine comprising a work-supporting bed, a reciprocating post, and a presser arm extending laterally from the post and movable therewith toward and away from the cutting bed to force dies through sheet material positioned upon the bed, thereby to form blanks. Various features of the invention disclosed but not claimed hereinafter constitute the subject-matter of applications for United States Letters Patent, Serial No. 692,513, filed October 6, 1933, in the name of Milton H. Ballard, Serial No. 751,030, filed November 1, 1934, in the names of Milton H. Ballard and Donald G. McLean, and Serial No. 755,685, filed December 3, 1934, filed in the names of said Ballard and McLean.

It is an object of the present invention to provide an improved machine of the type referred to which, without sacrificing the characteristic advantages of such machines heretofore in use, will be so constructed and arranged that increased economy in the cutting of blanks will be effected and that the performance of operations by use of the machine as well as the adjustment and servicing of the parts thereof will be facilitated.

To this end, the invention provides a machine of the afore-mentioned type having a frame, and a cutting bed mounted for movement in the frame, together with mechanism for adjusting the position of the bed heightwise of the frame comprising a shaft having a rack, and pawl normally operative to engage the rack to prevent rotation of the shaft, a lever for rotating the shaft, and means carried by the lever for releasing the pawl. This construction is advantageous in that it provides readily operable means for rapidly adjusting the position of the cutting bed relatively to the frame and for retaining the bed in adjusted position during operations of the machine.

The invention in its various aspects is disclosed in the following detailed description and

in the accompanying drawings and is pointed out in the claims.

In the drawings:

Fig. 1 is a side elevation of a machine illustrating one embodiment of the invention;

Fig. 2 is a front elevation of the machine with certain parts thereof shown in cross-section;

Fig. 3 is a cross section taken along line III—III of Fig. 2 illustrating the mechanism for adjusting the height of the bed;

Fig. 4 is a view taken along the line IV—IV of Fig. 2 and illustrates details of the bed-locking mechanism;

Fig. 5 is a plan view of the upper end of the frame showing the upper bearing for the post;

Fig. 6 is a cross sectional view taken along lines VI—VI of Fig. 5;

Fig. 7 is a side view partly in section illustrating the clutch-controlling mechanism;

Fig. 8 is a side elevation partly in section illustrating the motor drive mechanism;

Fig. 9 is a cross-section taken through the lower portion of the motor bracket showing details of the bracket-locking device;

Fig. 10 is a detail view of a part of the bracket-locking device; and

Figs. 11, 12, 13, and 14 are diagrammatic views illustrating the operation of the presser member and cutting bed.

As illustrated in Figs. 1 and 2 of the drawings, the machine comprises a C-shaped frame 10 upon one side of which is slidably mounted a hollow upright post 12 to which is secured a presser member or arm 14 arranged for co-operation with a second presser member, in the form of a cutting bed 16 mounted upon the opposite side of the frame, to apply pressure to work, such as leather or other sheet material, positioned upon the bed. As is customary in machines of this type, the post 12 is movable angularly about its axis so that the presser arm 14 secured thereto can be moved over the bed 16 about the axis of the post, for example, into operative position relatively to a freely movable cutting die located upon the work. The post is arranged to be reciprocated vertically by a connecting rod 18 operatively connected to an eccentric 21 upon a rotary shaft 20 which is controlled by a one-revolution clutch 22 adapted to cause engagement of the shaft 20 with a fly-wheel 24. ciprocation of the post 12 results in movement of the presser arm 14 toward and then away from the bed in a pressure-applying operation effective to force the die through the work to produce a blank.

The presser arm 14 comprises an integral casting located substantially entirely upon one side of the post 12 and secured thereto by clamping members 26. The arm extends freely over the central portions of the frame 10 and is of such length that it can be swung into a position in which its flat striking surface 28 overlies any desired portion of the cutting bed. The arm is so designed that its effective cross-section increases from its free end to a point near the axis of the post with the result that the stiffness of the arm under load increases as the point of application of the load upon the striking face 28 is brought closer to the axis of the post 12. Consequently, the maximum deflection of the arm under a given load upon the striking face 28 occurs when the load is applied to the extreme outer end of the arm, and the deflection is practically negligible when the same load is applied to the striking face near the axis of the post.

The body portion of the bed 16 comprises a casting having a flat cutting-block support 30 mounted upon a hollow column 32 which is slidably positioned in an enlarged portion 34 of the frame 10. The frame portion 34 is provided with laterally extending ears 36 within which are located bushings 38 which support screw-shafts 40 extending upwardly substantially parallel to the axis of the column 32 and equally spaced laterally thereof. The upper portion of each of the shafts 40 is screw-threaded at 42 and engages a nut 44 secured by bolts 45 in an opening 46 in the under side of the bed 16, thereby supporting the bed in position above the frame. The support 30 carries a wooden cutting block 47 substantially co-extensive therewith and which is suitably secured thereto by bolts 48 (Fig. 1) which engage clamping irons 50 of the block. The forward portions of the bed 16 including the block 47 are located close to the plane of the axes of the screw-shafts 40, but the rearward portions of the bed extend freely toward the axis of the post 12 and overhang the central portions of the frame 10. Thus it will be seen that the forward portions of the bed are substantially rigidly supported against deflection during pressure applying operations whereas the rearward or overhanging portions of the bed are less rigidly supported and are subject to deflection in a downward direction under pressure applied by the presser arm 14. The bed 16 is provided with stiffening ribs 52 which extend from the column 32 diagonally across the under side of the support 30 to the corners of the bed, and other ribs 54 (Fig. 1) extending from the ribs 52 toward the sides of the block. The ribs 52 and 54 are so constructed and arranged that the freely extending portion of the bed is stiffened substantially to an equal extent at points equidistant from the axis of the post 12, the effective cross section of the bed increasing in thickness from the side of the bed nearest to the post to a maximum in the vicinity of the column 32. The bed is so designed relatively to the presser arm 14 that under load the bed remains substantially rigid when the yield of the arm is a maximum and yields increasingly as the arm stiffens, with the result that for a given stroke of the presser arm the pressure applied, for example, to a die supported on the cutting block 47 will be sub-

stantially constant for any position of the die upon the bed. For example, when a die is positioned upon the block 47 near the axis of the supporting column 32 and the presser arm is brought into position in which it overlaps the die and bed 5 and is reciprocated, the arm is engaged near its outer end and, under load, is subjected substantially to its maximum deflection whereas the bed 16 remains substantially rigid. On the other hand, if a die is placed on the cutting block adjacent to its inner edge, the bed 16, under load, is subjected to substantially its maximum deflection whereas the presser arm 14 is engaged near the axis of the post 12 and consequently is subject to slight deflection only. Thus, for various 10 positions of a die along the cutting bed at different distances from the axis of the post, the deflections under forces applied to the presser arm and bed during operation of the machine tend to balance each other, that is, the total 15 placement of the members engaging opposite sides of the die tends to remain constant. Furthermore, if a die is successively located on the cutting block at different points equi-distant from the axis of the post, in which positions the die 20 will be engaged by the same portion of the presser arm, the successive deflections of the bed and arm will be substantially the same. Consequently, the sum of the deflections of the portions of the arm and bed engaging the die will be substantially the same for any position of the die 25 upon the cutting block. The pressure applied to the die and consequently the penetration of the die into the cutting block will therefore be substantially the same for all positions of the die 30 on the block for a given position of the bed heightwise of the frame.

Means is provided for adjusting the bed 16 and cutting block 47 heightwise of the frame 10 or presser arm 14 whereby the depth of cut or 40 penetration of the die into the block can be regulated. To this end, each of the screw-shafts 40 has secured thereto a gear 56 (Figs. 2 and 3) arranged to engage worms 58 and 59, respectively, which are secured to a horizontal shaft 60 arranged for rotation by a hand-wheel 62. The shaft 60 extends through openings 64 in the frame portion 34 and through slots 66 in the column 32, the slots 66 being elongated to provide clearance for the shaft as the column is moved 50 up or down with the bed. Rotation of the hand-wheel 62 in a counterclockwise direction results in a raising of the bed and the cutting block and vice versa.

In order to provide for the leveling of the bed 55 casting relatively to the arm 14, means is provided for adjusting the shaft 60 relatively to one of the worms. To this end, the operative connection between the worm 58 and the shaft 60 comprises a collar 68 which surrounds the outer end 60 of the shaft 60 and is loosely coupled to the worm 58 by interlocking projections 61. The collar is secured to the shaft 60 by a pin 70 which can be inserted in any one of several openings 72 in the end of the shaft. In assembling the machine 65 or in correcting the setting of the bed, the bed is leveled by turning shaft 60, causing worm 59 and gear 56 in mesh therewith to raise or lower the right side of the bed 28, the collar 68 being disconnected from the worm 58 at this time so that the worm will not be effective to vary the position of the left side of the bed. The collar 68 is then moved along the shaft until the projections 61 of the shaft 60 and the worm 58 interengage, and the pin 70 is inserted in the nearest hole 72, thus 75

its original position, being guided by the inner wall of the wedge 120 so that the setting of the cap is not lost. To provide for taking up the cap bearing upon wear on the walls of the opening 114, the rear end of the cap is provided with a downwardly projecting ear 134 (Figs. 1 and 5) through which extends a set-screw 136 adapted to engage the frame 10. To take up the wear from the cap the set-screw is turned in a clockwise direction with the result that the cap is pulled rearwardly a sufficient amount to compensate for the wear, it being only necessary to loosen the bolts 132 and set-screw 136 prior to adjusting the cap.

The drive shaft 20 is arranged to be operatively connected at the will of the operator to a fly-wheel 24 (Figs. 1 and 7) driven by a motor 140 supported on the frame. The operative connection between the shaft and fly-wheel comprises a one-revolution clutch 22, for example, of the type

illustrated in United States Letters Patent No. 1,011,903, granted December 19, 1911, upon an application filed in the name of Arthur Bates, said clutch including a spring-pressed bolt 142

operation of which controls the clutch. The clutch is operated by means of a handle 144 mounted on the presser arm 14 and arranged to engage a lever 146 which has a forked end 148

making engagement with a link 150 which is pivoted at 152 on the frame and has a rearwardly

extending portion 154 to which is connected a link 156. The link 156 at its lower end is pivotally connected to a link 158 loosely carried on a stud 160. The stud 160 also carries a link 162 extending into position for engaging the clutch bolt 142

normally to hold it in the position in which the shaft 20 and fly-wheel 24 are disconnected. For

raising the link 162 to permit movement of the bolt 142 in effecting operation of the clutch, the link 162 carries a latch 164 pivoted thereto and

having a plate 166 normally arranged in position to be engaged by a plate 167 on the link 158 upon depression of the starting handle 144. Such operation results in the raising of the link 162 to effect operation of the clutch to cause engage-

ment of the fly-wheel and shaft. The latch 164 is provided with a tail portion 168 which is ar-

ranged to be engaged by a cam 170 on the fly-

wheel shortly after the latter commences to rotate, said cam being effective to rotate the latch 164

to release the link 158 permitting a spring 171 to force the link 162 back into position to disengage

the bolt 142 at the end of a single revolution of the shaft.

The motor 140 is controlled by mechanism in-

dicated generally by reference character 172 at the top of the frame 10, this mechanism being

operated by a hand lever 174 pivoted on the frame at 176 and having a switch button 178 effective

when the lever 174 is moved forwardly to close

the motor circuit. The lever 174 is held in op-

erative or inoperative position as the case may

be by a spring-pressed plunger 180 carried by

the frame and adapted to extend inwardly into

engagement with a portion 182 of the lever 174 to

retain it in the position to which it has been

moved.

In order to prevent tripping of the clutch lever

162 when the power is off, which might result

in injury to an operator or in damage to the

machine or to the work when the power is later

turned on, the latch 164 is arranged to be held

in inoperative position when the motor circuit

is open. To this end, the tail portion of the latch

164 is provided with a projection 184 adapted to

be engaged by a rocker arm 186 pivoted at 188

on the frame and operatively connected to the link 174 by a rod 190. When the lever 174 is moved rearwardly to open the motor circuit, the rod 190 is depressed with the result that the link 186 is rotated in a counterclockwise direction, 5 engaging the projection 184 and rotating the latch 164 out of operative position relatively to the link 158. Consequently, as long as the motor circuit is open, depression of the starting handle 144 will result merely in the rotation of 10 the link 158 on its shaft 160 without resulting in the tripping of the clutch. Thus, while the starting handle can be moved in such a way that the various parts will not be subjected to strain as they would be if it were held in locked po- 15 sition, no damage will result from its operation.

Preferably, and as shown in Figs. 2 and 8, the motor 140 is supported on a bracket 192 depend- 20 ing from a shaft 194 pivoted in ears 196. The fly-wheel 24 is provided with a circular rack 198 20 which is arranged to engage a pinion 200 on the motor, and has flanges 202 which act as guards to prevent injury to the teeth of the rack 198. These flanges would operate to prevent withdrawal of the fly-wheel unless the pinion and 25 fly-wheel were relatively movable laterally. Consequently, the pivoted motor bracket 192 makes it possible to move the pinion 200 out of the line of movement of the flanges when it is necessary to remove the fly-wheel from the shaft 20. 30 In order to lock the motor bracket in position with the pinion 200 in mesh with the rack 198, the motor bracket 192 is provided with a depend- 35 ing portion 204 having a slot 205 within which is positioned a retaining bar 206 (Figs. 2, 3, 9, and 35 10). The bar 206 is arranged for pivotal move- 10 ment about a shaft 208 and carries a spring 210 normally operative to force the motor bracket outwardly. The end of the bar 206 is provided with an elongated slot 212 within which is lo- 40 cated a retaining pin 214 which is supported in the portion 204 of the motor bracket. At one end of the slot 212 the bar 206 is provided with a tapered recess 216 adapted to receive a corre- 45 spondingly tapered portion 218 of the pin 214. The tapered portion 218 terminates in a shoulder 220 which, when the bracket 192 is swung out- 50 wardly from the frame of the machine, rides upon the outer side of the bar 206, the shoulder being forced into engagement with the bar by a spring 222 which surrounds a reduced end portion 224 of the pin 214. When it is desired to place the pinion 200 and the rack 198 in mesh, the motor bracket is pushed inwardly and the pin 214 slides along the slot 212 until the spring 222 55 forces the tapered portion 218 into the recess 216 of the bar, thus locking the bracket in position. The bracket is released by pulling the pin 214 outwardly by means of a handle 226 thus remov- 60 ing the tapered portion 218 from the recess 216, and permitting the spring 210 to force the bracket outwardly. This construction provides a convenient means whereby the removal of the fly- 65 wheel for servicing is facilitated.

The operation of the various parts of the ma- 65 chine will be clear from the foregoing descrip- 70 tion. The operator places sheet material such as leather upon the cutting block 47 forming the upper part of the bed 16 and positions a die 75 upon the work with the cutting edges of the die 70 in contact with the work. The presser arm 14 is then swung about the axis of the post 12 until the striking face 28 of the arm is positioned over the die. The starting handle 144 is then de- 75 pressed resulting in the engagement of the fly-

locking the worm 58 to the shaft in operative position with the bed in leveled position. By this construction both of the worms 58 and 59 are so positioned as to raise or lower the bed by means of the gears 56 while maintaining it level, but at the same time avoiding any likelihood of binding of the parts such as would make raising or lowering of the bed difficult.

The bed 16 is locked against downward movement by a pawl 74 (best shown in Fig. 4) mounted on a stud 76 on the machine frame. The pawl 74 is arranged to engage a circular rack 78 on the inner end of the shaft 60 and is normally forced into engagement with the rack by a spring 80. A lever 82 is provided for releasing the pawl 74 when it is desired to vary the position of the bed 16. This lever is loosely mounted on the shaft 60 and is provided with a flat cam surface 84 and a curved cam surface 86 adapted to engage a pin 88 on the pawl 74 upon clockwise rotation of the lever to force the pawl out of engagement with the rack and to maintain it out of engagement as long as the lever 82 is held in a forward position. By moving the lever forwardly through a small angle the cam surface 84 is operative to release the pawl and to hold it out of locking position so that the hand-wheel 62 can be rotated to raise or lower the bed 16 heightwise of the arm 14.

In some instances it may be that the machine becomes stalled, due to improper operation, in which case the presser member 14 is usually positioned at the lower end of its stroke and exerts tremendous pressure upon the bed 16. When this occurs the parts may be sprung to such an extent that it is difficult to turn the hand-wheel 62. In order to overcome this difficulty, the lever 82 is so arranged that it can be used to apply considerable force to the shaft 60 to release the bed. To this end, the lever 82 is provided with a pawl 90 pivoted on a stud 92 carried by the lever and normally forced toward the rack 78 by a spring 94. However, the pawl is normally maintained out of rack-engaging position by a curved cam surface 96 on the frame which engages a pin 98 on the pawl to hold the pawl in inoperative position. When the lever 82 is rotated outwardly through an angle of about 15°, the pin 98 of the pawl is moved past the cam surface 96 and the spring 94 forces the pawl into engagement with the rack 78, thus providing a connection between the lever and the shaft 60 whereby the shaft can be turned, the pawl 74 being held in inoperative position by cam 86. The lever 82 is of comparatively great length and consequently considerable force can be applied to the shaft to release the pressure on the bed and other parts including the gears 56 and worms 58 and 59. When the pressure has been released and the bed adjusted to operative position, the lever 82 is swung rearwardly and a flat cam surface 100 engages the pin 98 of the pawl 90, removing the pawl from engagement with the rack, and upon further rearward movement of the lever the pin 98 of the pawl 74 drops off the cam surface 84 and permits return of the pawl 74 into engagement with the rack 78 to lock the bed in position. It is to be noted that, when under normal conditions the height of the bed 16 is to be adjusted, upon a slight forward movement of the lever 82, both pawls 74 and 90 are held disengaged from the rack 78 by cam surfaces 84 and 100, respectively. The lever 82 is provided with a spring-pressed plunger 101 (Fig. 2) adapted to be engaged by a lug 102 on the machine frame for retaining the lever rearwardly, in which position the bed is locked rigidly to the frame, or for

retaining the lever in slightly rotated position with both pawls released from the rack.

To facilitate the handling of sheet material, the machine is provided with a trough 103 positioned upon the frame between the post 12 and the bed 16, the overhanging portion of the bed providing adequate clearance so that a considerable amount of material can be positioned in the trough out of the way of the operator who may operate upon a portion of the material which is drawn over the inner edges of the block 47 on to its upper surface, the material being conveniently held in position by a clamping device such as clamp 104.

As above stated, the post 12 is slidably mounted for reciprocation in the frame. To facilitate the assembly of the post in the machine and to provide for convenient removal of the post when necessary to service it, the bearings for the post are so constructed and arranged that the post can be inserted or removed without disturbing other parts of the machine. To this end, the lower end of the post extends through a bearing formed in a projection 105 (Fig. 1) on the upper portion of the frame 10 and near its upper end is engaged on one side by a semi-annular bearing 106 which is positioned to take the lateral thrust of the post under the load caused by the operation of the presser arm 14 upon the work. The extreme upper end of the post is reduced in size forming a cylindrical member 108. This cylindrical member is engaged by a bearing in the form of a cap 110 (Figs. 1, 5, and 6) positioned upon the extreme upper portion of the frame 10. Since the greater portion of the lateral thrust to which the post is subjected is taken by the bearing 106, the periphery of the cylindrical member 108 is cut away or relieved on the side remote from the presser member as indicated by reference character 112 so that it engages the walls of an opening 114 in the cap 110 only at the forward portions thereof, this being sufficient in view of the fact that the bearing at the upper end of the post is needed only to support the weight of the post and presser member 14 during such times as the presser member is not under load. The advantage of this construction is that the relieving of the member 108 will reduce the friction between it and the cap, thus reducing the amount of effort required to turn the post in moving the presser member over the cutting block 47 about the axis of the post.

The cap or bearing 110 is positioned upon a seat 116 which is provided with tapered lateral walls 118, the cap being held in position by means of wedges 120 and 122 which are forced between the side walls of a central rib 124 of the cap and the walls 118. In initially positioning the cap, the post and presser member are located with the post in substantially vertical position by blocking up the presser member. The cap is adjusted transversely and longitudinally on the seat 116 until the opening 114 is located over the cylindrical portion 108. The wedges 120 and 122 are then driven in and are secured in position respectively by a bolt 126 located in an opening in the cap and which passes through an elongated opening 128 in the wedge 120, and by a set-screw 130 which passes through the cap and engages the wedge 122. The cap is further secured in position by bolts 132 which pass through the cap and into the frame 10. If for any reason the presser member is to be removed, the cap 110 is taken off by removing the bolts 132 and withdrawing the wedge 122, the wedge 120 being left in position. Then when the post is replaced the cap is returned to

wheel 24 with the shaft 20, thus causing a reciprocation of the post and presser member thereby to force the die through the work and into the cutting block. The operation of the presser arm 14 and the cutting bed 16 is illustrated in further detail by Figs. 11, 12, 13, and 14. These figures are diagrammatic only and very greatly exaggerate the action of the various parts. The full lines in Figs. 11, 12, and 13 indicate the relative positions of the presser arm 14, the cutting bed 16 and a die 228 at the point in the cycle of operations of the presser member in which the striking face 28 of the presser member is in its lowermost position. In these figures the dotted lines indicated by reference characters 230 represent the position of the presser member 14 upon its initial engagement with the die in each case. Reference characters 232 in Figs. 11 and 12 indicate the position which the presser member would assume at the end of its stroke if the arm were not deflected due to resistance of the die to the movement of the member. Reference character 234 indicates the normal position of the cutting bed 16 when it is not deflected under load. Reference character 236 in Figs. 12 and 13 indicates the position of the cutting bed which it has taken as a result of deflection under load.

In the case illustrated in Fig. 11 it will be observed that the die 228 has been placed upon the cutting block in the vicinity of the axis of the column 32 in which case the resulting deflection of the bed is so small that it can be neglected. At the same time the presser arm 14 is engaged by the die close to its outer end with the result that the amount of deflection of the arm represented by *a* is substantially at a maximum. This results in the forcing of the die into the cutting block by a slightly greater amount on the side of the die nearest the axis of the post. In Fig. 12 it will be observed that the die has been located centrally of the cutting block with the result that under load the bed has been deflected by an amount *b* whereas the arm 14 which engages the die a considerable distance inwardly of its end has been deflected by an amount *a'*. The deflections referred to are substantially equal and consequently the die has penetrated the cutting block to the same extent throughout the length of the die. In Fig. 13 the die has been placed on the cutting block near its inner edge portion, that is, near the axis of the post and under load the bed has been deflected by a still greater amount *b'* but, since the die is engaged by the presser arm quite close to the axis of the post, the deflection of the arm is practically negligible. In view of the fact that the bed was deflected substantially to its maximum amount whereas the arm was not appreciably deflected, the penetration of the die will be slightly greater on the portion thereof away from the axis of the post. As illustrated by Fig. 14, letters *c*, *d*, and *e* indicate the approximate position of the die 228 corresponding respectively to its positions shown in Figs. 11, 12, and 13, in which the die is shown in various positions along the central line of the block which passes through the axis of the post. The line 238 represents the central line of the presser arm 14 when it is swung laterally over the block to an angle of about 30° relatively to the central line of the block. If the die were placed successively at points *c'*, *d'*, and *e'*, which are located along the line 238 at the same distances from the axis of the post respectively as the points *c*, *d*, and *e*, the effect due to deflections of the arm and bed will be substantially the same as illustrated in Figs. 11, 12, and

13. For example, the deflection of the arm when the die is positioned at *c'* will be substantially the same as that when the die is positioned at *c*. Since the point *c'* is located a greater distance from the axis of the column 32 than the point *c*, it might be supposed that the deflection of the bed would be substantially greater when the load is applied at *c'*. This is not the case, however, for the reason that the reinforcing ribs 52 serve to stiffen the bed in directions extending angularly 10 of the central line of the cutting block. As a result of this, the deflection of the bed is approximately the same along an arc which has the axis of the post as a center, and, since a die positioned on the block anywhere along the arc engages the 15 presser arm at the same point, the deflection of the arm will likewise be substantially the same with the result that the penetration of the die will be substantially uniform along said arc. In view of all this, it should be apparent that the compensating deflections of the presser arm and bed produced when the die is placed in different positions anywhere on the cutting-block surface will result in substantially the same penetration of the die into the cutting block for a given initial 25 position of the bed heightwise of the arm.

In adjusting the height of the presser arm 14 for a die of given height, the arm is adjusted heightwise of the block through operation of the hand-wheel 62 and its associated mechanism into 30 such position that at the end of the stroke of the presser member the die will be forced into the block a slight distance, in practice, from one-sixteenth to three-sixteenths of an inch. The presser arm will then be operative to perform 35 cutting operations with the die in any position on the block and will be effective to perform such operations in a uniform manner over the entire surface of the cutting block.

Having described the invention, what we claim 40 as new and desire to secure by Letters Patent of the United States is:

1. A clicking machine comprising a frame, a post mounted for reciprocation in the frame, a presser arm carried by the post, a cutting bed, 45 means for supporting the bed upon the frame in operative relation to the presser arm comprising a plurality of screw shafts, a transverse shaft, gears connecting the transverse shaft with the screw shafts for rotating the latter to effect ad- 50 justment of the bed heightwise of the frame and presser arm, a rack on the transverse shaft, a pawl pivotally mounted on the frame and ar- 55 ranged to engage the rack for locking the bed in adjusted position, a lever loosely mounted on the transverse shaft, a cam on the lever for releasing said pawl upon angular movement of the lever, a second pawl pivotally mounted on the lever, and a cam on the frame normally operable to retain the second-mentioned pawl in inoperative posi- 60 tion but operable upon angular movement of the lever to a predetermined extent to permit move- 65 ment of said pawl into engagement with the rack whereby the lever is effective upon further rotation to cause rotation of the transverse shaft. 65

2. A clicking machine comprising a frame, a cutting bed carried by the frame, means for adjusting the position of the cutting bed heightwise of the frame comprising a plurality of screw shafts and a transverse shaft for operating the 70 screw shafts, a pawl for locking the transverse shaft in fixed position, a lever loosely mounted on the transverse shaft, a pawl carried by the lever for engaging the shaft whereby the lever can be operated to rotate the shaft, means for normally 75

5 maintaining the first-mentioned pawl in engagement with the shaft and for maintaining the second-mentioned pawl out of engagement with the shaft, and means for releasing the first-mentioned pawl and for causing engagement of the second-mentioned pawl with the shaft upon angular movement of the lever to a predetermined extent whereby the lever is rendered operative for turning the transverse shaft.

10 3. A clicking machine comprising a frame, a

cutting bed mounted for movement heightwise of the frame, means for adjusting the position of the bed heightwise of the frame comprising a shaft, a rack on the shaft, a pawl mounted upon the frame normally operative to engage the rack for preventing rotation of the shaft, a lever for rotating the shaft, and means carried by the lever for releasing the pawl.

MILTON H. BALLARD.

DONALD G. MCLEAN. 10

CERTIFICATE OF CORRECTION.

Patent No. 2,021,138.

November 19, 1935.

MILTON H. BALLARD, ET AL.

It is hereby certified that error appears in the above numbered patent requiring correction as follows: In the grant and heading to the drawing and specification, title of invention, for the word "METAL" read MATERIAL; and that the said Letters Patent should be read with this correction therein that the same may conform to the record of the case in the Patent Office.

Signed and sealed this 7th day of January, A. D. 1936.

Leslie Frazer

(Seal)

Acting Commissioner of Patents.
